A garbage storage device includes a base, a bin, a pedal, a lid, a linkage, a buffer and a guide. The bin is installed on the base. The pedal is mounted on the bin. The lid is mounted on the bin. The linkage includes a crankshaft and a rod. The crankshaft includes a shaft mounted on the base, a first crank extending from the shaft for contact with the pedal and a second crank extending from the shaft. The rod includes a middle portion, a first end extending from the middle portion into connection with the second crank and a second end extending from the middle portion into connection with the lid. The buffer includes a first end connected with the base and a second end connected with the first end of the rod. The guide is mounted on the base for guiding and ensuring smooth movement of the first end of the rod.

GARBAGE STORAGE DEVICE

FIELD OF INVENTION

The present invention relates to a garbage storage device including a lid and a buffer for the lid.

BACKGROUND OF INVENTION

People dispose of garbage in garbage bins. Some of the garbage stinks some time after the disposal. Therefore, some of the garbage bins are equipped with lids in order to keep the odor of such garbage therein. In some other cases, people use garbage bins equipped with lids simply to conceal garbage contained therein.

Some lids can be removed from garbage bins. However, such a lid causes a user troubles since he or she has to hold the lid during disposal of garbage or find a place to lay the lid on before disposal of garbage.

A conventional garbage storage device includes a base, a bin installed on the base, a pedal pivotally mounted on the bin and a lid pivotally mounted on the bin. A linkage is arranged between the pedal and the lid. The linkage includes a crankshaft and a rod. The crankshaft is pivotally mounted on the base. The crankshaft includes a first end in contact with the pedal and includes a second end. The rod includes a first end connected with the second end of the crankshaft and a second end connected with the lid. In specific, the second end of the crankshaft defines an aperture for receiving the first end of the rod. Thus, the pedal can be trodden in order to lift the lid through the linkage. However, closing the bin with the lid often makes a loud noise.

Taiwanese Patent Publication No. 429965 discloses conventional storage apparatus. This conventional garbage storage apparatus includes an internal bin, an external bin 1 in which the internal bin is put, a base 2 on which the external bin 1 is mounted, a lid 6 pivotally mounted on the external bin 1, a pedal 11 pivotally mounted on the base 2 and a linkage connected between the lid 6 and the pedal 11. The linkage includes a crankshaft 3, a joint 4 and a rod 5. The crankshaft 3 includes a shaft mounted on the base 2, a first crank extending transversely from the shaft for contact with the pedal 11 and a second crank extending transversely from the shaft for connection with the joint 4. The joint 4 includes a first socket in which the second end of the crankshaft 3 is fit, a second socket extending transversely from the first socket in order to receive the rod 5, a rod 41 extending transversely from the sleeve and a piston 42 attached to the rod 41. Referring to FIGS. 4-6, on the base 2 is formed a cylinder 21 for receiving the piston 42. Thus, the cylinder 21 cooperates with the piston 42 in order to work as an air buffer. The cylinder 21 defines, near its bottom, a hole 22 through which air can flow into and from the cylinder 21 slowly. However, as best shown in FIG. 6, when the crankshaft 3 is pivoted, the joint 4 is bent, thus interfering movement of the piston 42 in the cylinder 21. In practice, the piston 42 is often stuck in the cylinder 21, thus prematurely stopping the lid 6 before it closes the external bin 1. Furthermore, to accommodate the cylinder 21, the base 2 must be made thick, thus increasing its cost.

The present invention is therefore intended to obviate or at least alleviate the problems encountered in the prior art.

SUMMARY OF INVENTION

It is an objective of the present invention to provide a garbage storage device that can be moved slowly and smoothly from an open position to a closed position.

2

According to the present invention, a garbage storage device includes a base, a bin, a pedal, a lid, a linkage, a buffer and a guide. The bin is installed on the base. The pedal is mounted on the bin. The lid is mounted on the bin. The linkage includes a crankshaft and a rod. The crankshaft includes a shaft mounted on the base, a first crank extending from the shaft for contact with the pedal and a second crank extending from the shaft. The rod includes a middle portion, a first end extending from the middle portion into connection with the second crank and a second end extending from the middle portion into connection with the lid. The buffer includes a first end connected with the base and a second end connected with the first end of the rod. The guide is mounted on the base for guiding and ensuring smooth movement of the first end of the rod.

Other objectives, advantages, and novel features of the invention will become more apparent from the following detailed description when taken in conjunction with the attached drawings.

BRIEF DESCRIPTION OF DRAWINGS

The present invention will be described through detailed illustration of embodiments referring to the attached drawings.

FIG. 1 is a perspective view of a garbage storage including a bin, a lid and a buffer for the lid according to a first embodiment of the present invention.

FIG. 2 is an exploded perspective view of the buffer used in the garbage storage device shown in FIG. 1.

FIG. 3 is a cross-sectional view of the garbage storage device shown in FIG. 1.

FIG. 4 is a cross-sectional view of the garbage storage device shown in FIG. 1, showing the buffer in a first position.

FIG. 5 is another cross-sectional view of the garbage storage device of FIG. 4.

FIG. 6 is a cross-sectional view of the garbage storage device shown in FIG. 1, showing the buffer in a second position.

FIG. 7 is another cross-sectional view of the garbage storage device of FIG. 6.

FIG. 8 is a cross-sectional view of the garbage storage device shown in FIG. 1, showing the buffer in a third position between the first and second positions.

FIG. 9 is another cross-sectional view of the garbage storage device of FIG. 8.

FIG. 10 is an exploded perspective view of a buffer used in a garbage storage device according to a second embodiment of the present invention.

FIG. 11 is a cross-sectional view of the garbage storage device shown in FIG. 10, showing the buffer in a first position.

FIG. 12 is a cross-sectional view of the garbage storage device shown in FIG. 10, showing the buffer in a second position.

FIG. 13 is a cross-sectional view of the garbage storage device shown in FIG. 10, showing the buffer in a third position between the first and second positions.

DETAILED DESCRIPTION OF PREFERRED EMBODIMENTS

Referring to FIG. 1, a garbage storage device 2 includes a base 4, a bin 6 installed on the base 4, a pedal 8 pivotally mounted on the bin 6 and a lid 10 pivotally mounted on the bin 6.

FIG. 2 shows a linkage 12 arranged between the pedal 8 and the lid 10 shown in FIG. 1. The linkage 12 includes a crankshaft 14 and a rod 16. The crankshaft 14 includes a shaft (not numbered) mounted on the base 4, a first crank 11 extending transversely from the shaft for contact with the pedal 8 and a second crank 13 extending transversely from the shaft and defining a hole 15. The rod 16 includes a middle portion (not numbered), a first end 17 extending transversely from the middle portion into the hole 15 and a second end 19 connected with the lid 10. Thus, the pedal 8 can be trodden in order to lift the lid 10 through the linkage 12.

FIG. 2 further shows a buffer 18 according to the preferred embodiment of the present invention for use in the garbage storage device 2 shown in FIG. 1. The buffer 18 is arranged between the base 4 and the linkage 12.

For pivotal connection with the buffer 18, the base 4 includes two ears 20 each defining a hole 22.

The buffer 18 includes a first cylinder 24, a second cylinder 36 and a spring 34 including a first end inserted in the first cylinder 24 and a second end inserted in the second cylinder 36.

The first cylinder 24 includes a closed end and an open end. The first cylinder 24 includes an ear 26 formed at the closed end. The ear 26 defines a hole 28. The ear 26 is located between the ears 20. A pin 21 is inserted through the holes 22 and 28. Thus, the first cylinder 24 is pivotally mounted on the ears 20. A thread 25 is formed on the first cylinder 24 near the open end.

The second cylinder 36 includes an open end and a closed end. The open end of the second cylinder 36 is inserted in the open end of the first cylinder 24 through a ring 27. A ring 32 is received in a groove 30 extending around the second cylinder 36 near the open end. The ring 27 includes a thread 31 formed on an internal face thereof for engagement with the thread 25 formed on the first cylinder 24. Thus, the open end of the second cylinder 36 is retained in the open end of the first cylinder 24, and the spring 34 is in and between the first cylinder 24 and the second cylinder 36.

A tube 38 extends transversely from the closed end of the second cylinder 36. The tube 38 defines a hole 39 through which the first end 17 of the rod 16 extends. The first end 17 of the rod 16 is inserted in the hole 39 of the tube 38. Thus, the second cylinder 36 is pivotally connected with the rod 16.

A guide 40 is installed on the base 4. The guide 40 defines a slot 41 in which the first end 17 of the rod 16 is inserted. As best shown in FIG. 3, the first end 17 of the rod 16 can slide in and along the slot 41. The slot 41 extends in compliance with the curved trajectory of the first end 17 of the rod 16. Thus, smooth movement of the first end 17 of the rod 16 is ensured by the guide 40.

The buffer 18 and the guide 40 may be covered by a shelter 29 installed on the base 4.

A guide 40 is installed on the base 4. The guide 40 defines a slot 41 in which the first end 17 of the rod 16 is inserted. As best shown in FIG. 3, the first end 17 of the rod 16 can slide in and along the slot 41. The slot 41 extends in compliance with the curved trajectory of the first end 17 of the rod 16. Thus, smooth movement of the first end 17 of the rod 16 is ensured by means of the guide 40.

The buffer 18 and the guide 40 may be covered by means of a shelter 29 installed on the base 40.

FIGS. 4 and 5 show the garbage storage device 2 in a closed position where the buffer 18 shrinks. The spring 34 is compressed.

Referring to FIGS. 6 and 7, the lid 10 is pivotally moved until the garbage storage device 2 reaches a fully open position. The buffer 18 fully extends and the spring 34 is not compressed.

Referring to FIGS. 8 and 9, the lid 10 is released. The lid 10 falls due to its weight. The movement of the lid 10 is buffered or hindered via the buffer 18 since they are both connected with the linkage 12.

FIGS. 10~13 show a buffer 18 according to a second embodiment of the present invention. In the second embodiment, a connecting rod 33 and a piston 35 are used instead of the second cylinder 36, and oil instead of the spring 34. The piston 35 is secured to the connecting rod 33. The piston 35 defines two holes 44. A ring 46 is mounted on the piston 35. The oil is filled in the cylinder 24. A seal 37 is provided between the cylinder 24 and the ring 27 for retaining the oil in the cylinder 24.

The present invention has been described through detailed illustration of the preferred embodiment. Those skilled in the art can derive many variations from the preferred embodiment without departing from the scope of the present invention. Therefore, the preferred embodiment shall not limit the scope of the present invention. The scope of the present invention is defined in the attached claims.

What is claimed is:

1. A garbage storage device including:

a base;

a bin installed on the base;

a pedal mounted on the bin;

a lid mounted on the bin;

a linkage including a crankshaft and a rod, the crankshaft including a shaft rotatably mounted on the base a first crank extending from the shaft for contact with the pedal and a second crank extending from the shaft, the rod including a middle portion, a first end extending from the middle portion into a connection with the second crank and a second end extending from the middle portion into connection with the lid, with the connection of the rod first end with the second crank moving in a curved trajectory;

a buffer including a first end connected with the base and a second end connected with the first end of the rod, with spacing between the first and second ends of the buffer changing with movement of the connection of the rod first end with the second crank in the curved trajectory; and

a guide mounted on the base, with the first end of the rod sliding along and being guided by the guide while moving in the curved trajectory and ensuring smooth movement of the first end of the rod in the curved trajectory.

2. The garbage storage device according to claim 1 wherein the guide defines a slot for receiving the first end of the rod.

3. The garbage storage device according to claim 1 wherein the second crank defines a hole through which the first end of the rod extends.

4. The garbage storage device according to claim 1 wherein the second end of the buffer defines a hole through which the first end of the rod extends.

5. The garbage storage device according to claim 1 wherein the buffer includes a spring connected between the base and the first end of the rod.

6. The garbage storage device according to claim 5 wherein the buffer includes a first cylinder including a closed

5

end connected with the base and an open end through which the spring extends and a second cylinder including an open end through which the spring extends and a closed end connected with the first end of the rod.

7. The garbage storage device according to claim 6 wherein one of the first and second cylinders is partially inserted in the other one of the first and second cylinders. 5

8. The garbage storage device according to claim 7 wherein the second cylinder is partially inserted in the first cylinder. 10

9. The garbage storage device according to claim 8 wherein the buffer includes a ring mounted on the second cylinder. 15

10. The garbage storage device according to claim 9 wherein the buffer includes a groove around the second cylinder for receiving the ring. 20

11. The garbage storage device according to claim 6 wherein the base includes two ears formed thereon, and the first cylinder includes an ear formed at the closed end and mounted on the ears of the base. 25

12. The garbage storage device according to claim 11 including a pin fit in a hole defined in each of the ears and a hole defined in the ear of the first cylinder. 30

13. The garbage storage device according to claim 6 wherein the second cylinder includes a tube transversely 25 extending from the closed end for receiving the first end of the rod.

14. The garbage storage device according to claim 1 wherein the buffer includes: 35

6

a cylinder including a closed end connected with the base and an open end; oil filled in the cylinder;

a piston sliding in the cylinder and defining at least one hole through which the oil can flow slowly; and

a connecting rod including a first end connected with the piston and a second end connected with the first end of the rod. 10

15. The garbage storage device according to claim 14 including a ring engaged with the cylinder, thus retaining the piston in the cylinder. 15

16. The garbage storage device according to claim 15 including a seal installed between the ring and the cylinder. 20

17. The garbage storage device according to claim 14 including a ring mounted on the piston. 25

18. The garbage storage device according to claim 14 wherein the base includes two ears formed thereon, and the cylinder includes an ear formed at the closed end and mounted on the ears of the base. 30

19. The garbage storage device according to claim 14 including a pin fit in a hole defined in each of the ears and a hole defined in the ear of the first cylinder. 35

20. The garbage storage device according to claim 14 including a tube extending from the connecting rod for receiving the first end of the rod. 40
